UNITED STATES PATENT OFFICE.

GEORGE A. LEFORT, PENTALEON DUBÉ, AND L JOSEPH ST. PIERRE, OF MONTREAL,
QUEBEC, CANADA.

TOOL FOR RESEATING AND RESURFACING VALVES AND THE LIKE.

Application filed September 26, 1921. Serial No. 503,434.

To all whom it may concern:

Be it known that we, GEORGE A. LEFORT, PANTALEON DUBÉ, and L JOSEPH ST. PIERRE, subjects of the King of Great Britain, residing at Montreal, in the Province of Quebec, Canada, have invented certain new and useful Improvements in Tools for Reseating and Resurfacing Valves and the like; and we do hereby declare that the following is a full, clear, and exact description of the invention, such as will enable others skilled in the art to which it appertains to make and use the same.

The present invention relates to new and useful improvements in tools for reseating and resurfacing valves and the like.

The primary object of the invention is the provision of a tool which can be used for resurfacing the valves and also for reseating the same.

Another object of the invention is the provision of a tool such as above referred to, including a plurality of reversible cutters which when in one position can be used to resurface the valve and when in the opposite position can be used for forming a new seat.

Still another object of the invention is the provision of a tool such as above referred to which will be comparatively simple and inexpensive to manufacture, reliable and efficient in use, and readily operated.

With the above and other objects in view the present invention resides in the novel features of construction, formation, combination and arrangement of parts to be hereinafter more fully described, claimed and illustrated in the accompanying drawing forming a part of the present application, and in which:

Figure 1 is a side elevation of the tool;
Figure 2 is a longitudinal sectional view thereof;

Figure 3 is a perspective view of one of the cutters removed;

Figure 4 is a top plan view thereof;

Figure 5 is a view showing the tool used to resurface the seat; and,

Figure 6 is a similar view showing the tool used to resurface the valve.

Referring now to the accompanying drawing by corresponding characters of reference throughout the several views, the numeral 7 designates in general our improved tool which consists of a cylindrical body portion 8 having spaced openings 9 formed therein

the lower ends of which receive threaded plugs 9' for regulating the depth of these openings 9. Side openings 10 are likewise provided which enter into the openings 9' for the purpose of engaging the tools and holding them rigidly in the desired position.

The lower portion of the body is squared or formed angular as at 12 in order that the same may be clamped in a vise or the like. A central opening 13 is provided in the body portion 7 and is provided with a bushing 14 which may be renewed in case of wearing.

In operation for reforming a new surface 70 on the valve the cutting elements 11 are locked in the positions shown in Figures 1, 2, 4 and 6, and the stem 15 of the valve is threaded through the bushing 14 so that the beveled surface 16 of the head 16' engages the cutting edges 17 of the elements 11. By rotating the valve the old surface will be removed therefrom and the new surface cut thereon. In using the tool for resurfacing the seat the cutting elements 11 are reversed as shown in Figure 5 and a valve stem 18 may be inserted upwardly through the opening in the bushing 14 and the cage which has the seat 19 at its upper end placed over this stem 18. By rotating the 85 cage 20 a new valve seat 19 will be cut.

Obviously the opposite sides of the elements 11 are flat so that the screws which pass through the threaded openings 10 will lock them in both positions against displacement.

From the foregoing description taken in connection with the accompanying drawing it will be manifest that a valve reseating tool is provided which will fulfill all of the 95 necessary requirements of this device, and it should be understood in this connection that various minor changes in the specific details of construction can be resorted to within the scope of the appended claims, 100 without departing from the spirit or sacrificing any of the advantages of the invention.

Having thus fully described the invention, what we claim as new and desire to protect by Letters Patent is:

1. The herein described tool comprising a body portion having a central opening therein, spaced openings arranged concentrically with reference to the central open- 110

ing in the body, cutting tools mounted in said openings, screws engaging the cutting elements for locking them against displacement, screws threaded in the bottoms of the 5 openings for regulating the depth thereof.

2. The herein described tool comprising a body portion having a concentric opening arranged therein, reversible cutting elements located in said openings, screws passing 10 through the sides of the body portion and entering the openings for engagement with the cutting elements and locking them in position, screws threaded in the bottoms of the openings for regulating the height 15 of the cutting elements, substantially as and for the purposes set forth.

3. The herein described valve tool comprising a body portion having a central opening formed therein, and concentric 20 openings spaced diametrically with reference to the central opening, and concentric

thereto, a bushing disposed in the central opening of the body portion, the lower side of said body portion being squared to form supporting means, locking screws passing 25 through the sides of the body portion, entering the openings formed therein, cutting elements mounted in the openings and locked in position by said screws, the opposite sides of said cutting elements being flattened, said cutting elements being reversible and vertical movable screws threaded in the bottom of said openings and regulating the vertical adjustment of the cutting elements, substantially as and for the purposes set 30 forth.

In witness whereof we have hereunto set our hands,

GEORGE A. LEEFORT
PANTALEON DUBÉ,
L JOSEPH ST. PIERRE.
